UNITED STATES PATENT OFFICE.

JOHN MARTENS, OF CHICAGO, ILLINOIS.

RADIATOR AIR VALVE.

Application filed October 8, 1923. Serial No. 667,137.

To all whom it may concern:

Be it known that I, JOHN MARTENS, a citizen of the United States, residing at Chicago, in the county of Cook and State 5 of Illinois, have invented a certain new and use Improvement in Radiator Air Valves, of which the following is a full, clear, concise, and exact description, reference being had to the accompanying drawings, forming a part of this specification.

The present invention relates to radiator air valves.

The fundamental object of the invention is to save fuel by providing an air valve 15 for steam radiators which will function in a new and improved manner to vent air out of the radiator or adjacent part of the system when the vapor or steam is first admitted, and to thereafter close the venting outlet 20 after the air is all vented. By providing an air valve which is sensitive and quickly responsive to vapor pressure, I am enabled to reduce fuel costs and to avoid the objectionable emission of steam, odors and water 25 into the room. A fuel saving is effected by reason of the fact that the present air valve will close when the vapor reaches it after all the air is discharged, whereas in the devices as heretofore made a substantial 30 steam pressure is required to seat the valve.

A further object is to provide such a radiator valve which will be of the greatest simplicity and cheapness of construction, and which will be readily applicable to all 35 standard radiators.

Referring to the accompanying drawings illustrating the preferred form of my invention;

The single figure is a vertical sectional 40 view of one of my improved radiator valves.

The device is assembled upon a cup-shaped fitting 5 which is formed with a lateral nipple 6 adapted to screw into the boss which is customarily provided on the end 45 of the radiator for receiving the valve. A tubular chamber 7 is screwed down into an internal thread formed in the top of the cup-shaped member 5. The upper end of the chamber 7 is converged inwardly to provide the reduced tubular neck 8 continuing upwardly. The upper end of this tubular neck is threaded externally for receiving a tubular cap 9, screwing down over the neck 8. The upper end of this cap 9 is closed 50 over with the exception of a vent outlet 11

in the center. These parts and connections are commonly known. A sleeve 13 is slipped down inside of the reduced neck 8 to guide the ball check valve 12. An inwardly extending bead 14 is preferably provided 60 at the juncture of the neck 8 and the chamber 7 for receiving the lower edge of the sleeve 13. The pressure abutment of the lower edge of this sleeve 13 on the bead 14 acts as a limiting stop for the downward 65 screwing of the cap 9, and also serves as a very effective seal for preventing the leakage of steam or vapor out of the sleeve. After the cap 9 has been screwed down to firmly seat the ends of the sleeve 13 the cap may be 70 soldered around its lower edge to the reduced neck 8 so as to prevent tampering with the valve and to provide a hermetic seal around the edge of the cap. A supporting rod 15 having its lower end suitably anchored in 75 the cup member 5, extends up into the sleeve 13 for supporting the ball check valve 12 in approximately the position shown.

The ball check 12 has a certain nicety of proportioning in weight relative to its size, and to the diameter of the sleeve 13 and the size of the vent outlet 11. This is to the end 80 of insuring the closure of the valve after the vapor has forced the air from the radiator and has reached the radiator air valve 85 due to the increase in the pressure of the vapor.

By virtue of the ready removability of the cap 9, it will be apparent that ball check 90 valves of different weights, and of different sizes, can be substituted in the sleeve cage 13 to adapt the device to closure of the valve at a certain pressure. Also, different caps can be substituted having different sized vent openings 11. For example, for 95 a radiator having 50 square feet of radiating surface the cap 9 would have a vent opening 11 of a certain size, and for a radiator of 100 square feet of radiating surface 100 a different cap having a different vent opening would preferably be substituted so as to allow all the air to be vented out of the radiator before the ball valve seated.

In its preferred form, the ball check valve 12 is preferably made with a diameter closely approaching that of the bore of the sleeve 13, so that the discharge of vapor or steam in appreciable quantities from the radiator will tend to form a liquid seal between the check valve and the wall of the sleeve 13, 110

whereby the pocketing action of this liquid seal will assist in raising the check valve to the vent opening 11.

I claim:—

- 5 1. In a radiator air valve of the class described, the combination of a tubular chamber adapted for connection with the radiator, a reduced neck at the upper end of said chamber, an inwardly turned bead forming a neck portion extending from said chamber, said neck portion having an inwardly turned bead forming an internal shoulder at the lower part thereof, a sleeve in said neck portion and resting on said internal shoulder, a cap fitted over the upper end of said neck portion, a vent opening in the upper end of said cap, a ball check valve having a diameter slightly less than the internal diameter of said sleeve adapted to seat on said vent opening, and a supporting rod for said check valve, the end of which is on substantially the same plane as the internal shoulder of said neck. 55
- 10 2. In a radiator air valve of the class described, a chamber, a neck portion extending from said chamber, said neck portion having an inwardly turned bead forming an internal shoulder at the lower part thereof, a sleeve in said neck portion resting on said internal shoulder, a cap fitted over the top of said neck portion, a vent in the top of said cap, a ball check valve confined within said sleeve, and a rod extending upwardly through said chamber and into said neck for supporting said valve in its lower position, said sleeve being relatively long to dis- 60
- 15 pose said vent opening considerably above the lower position of said ball valve, said ball valve being adapted to seat on said vent opening only after the air has been exhausted from the radiator and an effective vapor or steam pressure is impressed on said ball valve. 65
- 20 3. In a radiator air valve of the class described, the combination of a cup member, a tubular chamber fitted to said cup member, said tube chamber having a reduced neck portion at its upper end, an inwardly turned bead forming an internal shoulder in the lower part of said neck portion, a thread on the outside of said neck portion, a cap in- 70
- 25 ternally threaded screwing down over said neck, a sleeve abutting the top of said cap at its upper end and spaced from the walls thereof, said sleeve extending down within the bore of said neck and seating at its lower edge on said internal shoulder, a vent opening in the top of said cap substantially concentrically of said sleeve, a ball check valve confined within said sleeve, and means for supporting the 75
- 30 vapor or steam pressure is impressed on said ball valve. 80
- 35 4. In a radiator air valve of the class described, a chamber, a neck portion extending from said chamber, said neck portion having an inwardly turned bead forming an internal shoulder at the lower part thereof, a sleeve in said neck portion resting on said internal shoulder, a cap fitted over the top of said neck portion, a vent in the top of said cap, a ball check valve confined within said sleeve, and means for supporting the 85
- 40 vapor or steam pressure is impressed on said ball valve. 90
- 45 5. In a radiator air valve of the class described, a chamber including a neck portion, said neck portion having an internal shoulder at the lower part thereof, a sleeve in said neck portion resting on said internal shoulder, a cap fitted over the top of said neck portion, a vent in the top of said cap, a check valve confined within said sleeve, and means for supporting said check valve within the sleeve, said check valve being 95
- 50 adapted to remain unseated while air is discharged from the said vent and to close the said vent when the vapor reaches the check valve. 95

In witness whereof, I hereunto subscribe my name this 5th day of October, 1923.

JOHN MARTENS.
